UNITED STATES PATENT OFFICE.

GEORGE HOFMANN, OF CHICAGO, ILLINOIS, ASSIGNOR TO RALPH BARD, TRUSTEE, OF CHICAGO, ILLINOIS.

LEAD-PENCIL MECHANISM.

Application filed August 17, 1922. Serial No. 582,348.

To all whom it may concern:

Be it known that I, GEORGE HOFMANN, a citizen of the United States, residing at Chicago, in the county of Cook and State of Illinois, have invented certain new and useful Improvements in Lead-Pencil Mechanisms, of which the following is a specification.

My invention relates to mechanical-feed lead pencil structure, and has for its general object to provide a construction particularly adapted for mounting in the end of a fountain pen barrel, the pencil mechanism being made so short that, although it will handle a lead of adequate length, the portion of the mechanism entering the fountain pen barrel will occupy but a minimum amount of space within the barrel, and the exposed portion of the mechanism may be contained within the length of a fountain pen cap of convenient size.

More specific objects of my invention are to provide a construction that is simple and inexpensive from the standpoint of parts production and assembly, efficient and reliable in operation and easy to load, or replenish with lead.

Other and further objects of my invention will become apparent from the following description, taken in conjunction with the accompanying drawings wherein Fig. 1 is a central longitudinal section through the mechanism, with parts broken away for clearness; Fig. 2 is a transverse section on line 2—2 of Fig. 1; and Fig. 3 shows the tip, in section, partly removed from the operating mechanism, illustrated in side elevation.

Preliminarily it may be pointed out that for ease of understanding of the drawings I have, in Fig. 1, shown various parts which, in assembly, are secured together in immovable relation, as being pinned one to another, but in assembly practice these parts may be, and are intended to be, united by force fitting or up-setting as constituting more desirable forms of union.

In the drawings 10 indicates a fragment of a fountain pen barrel containing an ink sac, as indicative of any desired form of fountain pen structure in which it is desired to preserve as much as possible of the barrel free for ink storage, but to equip the barrel at its end opposite to the pen with a pencil mechanism. The pencil mechanism

12 comprises generally a feed mechanism 13 permanently seated in the barrel 10 and containing all of the operating parts by which a positive feed of a lead stick 14 may be effected, and a tip section 15 through the end opening of which said lead may be guided with an adequate frictional grip to hold it steady in writing, this tip structure being detachable from the feed mechanism without carrying therewith any of the feed-structure parts but carrying therewith in removal the lead stick.

The feed mechanism comprises a lead-guiding element 16 fixed in the barrel 10 and through which the lead stick will be fed to the tip orifice, a rotatable feed screw element 17 surrounding the lead-guiding element, this feed screw element being held in the barrel against longitudinal displacement, and being detachably connected with the tip and rotatable manually from the exterior of the mechanism; and a propeller element or feed nut 18, engaging the feed screw to be axially moved by rotation of the latter and entering the guide element to act upon the inner end of the lead stick.

In the specific construction shown the guide element 16 is a tube longitudinally slotted as at 19 from its forward end, which is close to the lead-orifice of the tip, substantially to its base end 19' which is preferably solid. To anchor this tube in the barrel 10, and to provide a seat in which the screw element 17 may be fixed against axial displacement but left free for rotation, I secure to the solid end of the tube a base 20 of disc form having a boss 21 of two diameters smaller than the disc diameter. A thimble 22, rigidly secured in the end of barrel 10 has its apertured bottom secured against the shoulder of the boss as by external washer 23, so that thimble, tube-base and lead tube are all anchored rigidly in the barrel 10, and there is left between the bottom of the thimble and the disc an annular recess of the base structure in which the screw structure may be rotatably secured.

Screw structure 17 provides an internally threaded tube or sleeve that at its forward end stops short of the end of lead-guiding tube 16 (as required by the taper of the tip) and is provided with a guide-ring 17' for the lead-tube, while at its rear end it is preferably expanded into a cupped head 24 which is secured to the cuff 25 of a turning-

piece 26 which is externally accessible and upon which the tip-structure 15 may be detachably carried. In the particular construction shown, the cuff 25 fits neatly within 5 in the thimble 22 and has its apertured, or inwardly-flanged, bottom engaged in the annular groove or recess between base-disc 20 and the bottom of the thimble 22, so that the cuff, together with its attached screw sleeve 10 is rotatable, but is anchored against axial displacement from the supporting barrel 10. The forward portion of this cuff provides, just beyond the forward end of the barrel 10 and thimble 22, a knurled turning ring 15 26, exteriorly accessible, and the front end of this ring is reduced, neatly to receive the open rear end of the detachable tip-shell!

The lead-propeller 18, completing the lead-propelling mechanism, is a cylindrical 20 nut to engage the screw threads of the screw-sleeve, and having a pair of arms 32 entering the side slots of the lead-guiding tube to carry, within the tube, the pushing stem 33 that engages the inner end of the lead-stick.

Manifestly, when this feeding mechanism is completely assembled and mounted in the barrel, rotation of the screw sleeve by means 30 of the turning ring 26 will advance or retract the nut 18 along the fixed lead-tube 16 which holds said nut against rotation and is itself guided and supported in the annular nut. The rather-fragile lead tube of course receives support also at its base end and it is 35 preferably supported near its forward end in the end ring 17' of screw sleeve 17. In use, no part of the feeding mechanism need ever be removed, and thus liability to loss or injury of parts is minimized.

40 The tip structure, which preferably is made removable for convenience in reloading, is a tapering shell preferably thickened at its forward end to provide a cylindrical bearing 35 for the lead-stick, this thickened 45 end being preferably slotted longitudinally as at 36 for a sufficient distance to make it yieldingly clamp upon the lead-stick to give a firm, non-wabbling writing-point. At its open rear end the tip-shell is shaped to slip 50 fit over the reduced part of the turning-ring 26, and adjacent said rear end there is secured in the tip-shell a tubular guide-structure 38 which may also serve to detachably connect the removable tip with the barrel-carried parts. Guide 38 is of suitable diameter 55 neatly to receive the slender, stem-like portion of the feed mechanism which projects forwardly beyond the turning member, and preferably such guide extends along the 60 screw-sleeve almost to the base of the latter. Part 38 therefore acts as a guide in assembling the tip with the barrel-carried parts, as graphically shown in Fig. 3, and insures 65 the straight alignment of parts, in placing the tip, which will prevent lead-breakage.

In the form shown, this tubular guide has at its outer end a cupped flange 39 which extends to and is secured in the tip-shell, and also said guide preferably has provision for making screw threaded engagement with the 70 turning part 26, well within the barrel-carried structure. Specifically, the guide may be long enough to reach almost to the cupped head 24 of the screw stem 17, and between its ends at a point in rear of the 75 open base of the tip-shell, it may be exteriorly threaded as at 40 for engagement with internal screw-threads 41 carried by the rotatable cuff 25. For manufacturing purposes it is desirable to form the threads 41 on a cuff-liner 42 that is securely fastened in the cuff.

It will be apparent that the tip structure may readily be removed from the barrel-carried feed mechanism as shown in Fig. 3 80 for reloading purposes, when, as I prefer, the slotted end of the tip snugly grips the lead-stick and the lead tube rather-loosely engages such lead, the tip will carry the lead with it on removal, as shown in Fig. 3. 85 On re-assembly, even when the lead so carried by the tip is long, the provision of the tubular guide insures that the rear of the lead will assuredly re-enter the lead-tube 90 without breakage. When one lead is exhausted, the propeller nut 18 should be backed to the bottom end of its screw sleeve 17, the tip removed, the new lead inserted in the lead tube 16, to project somewhat beyond its forward end, and the tip replaced. 95 Of course when the tip is replaced on the feed assembly, the stub of used lead is driven out by the end of the new lead.

100 It will be observed that by the structure described I provide a feed mechanism adequate to handle a lead of considerable length, in a structure so compact longitudinally that the portion entering the barrel 10 may be short -- approximately only the amount sufficient for strength of union between the barrel and pencil mechanism. Also it will be noted that many advantages are attained by refinements shown. The pencil mechanism is especially rugged, despite the desirably-light, thin-metal character of its parts, and presents always a firm, steady writing point. The tip structure, it will be seen, will never get loose or laterally-wabbly, because the fitting of the broad base of the tip-shell on the turning-ring in one plane and the threaded engagement of the tubular guide with the rotatable cuff-liner at a point well in rear of that plane gives a particularly strong, desirable joint.

110 While I have herein described in considerable detail a specific construction having advantageous details particularly adapting it for quantity production at minimum assembly-cost, and some details of which structure I may claim, it will be apparent 115 120 125 130

that in the broader aspects of my invention many changes may be made in details of construction without departure from the spirit of my invention and within the scope 5 of appended claims.

I claim:

1. In a pencil mechanism of the character described, the combination with a barrel, of a central lead-tube rigidly connected with 10 said barrel to be held by it against rotation, a propeller element having a portion entering said tube to act against the lead and having a portion outside of said tube adapted to engage a screw member to be propelled thereby, a screw member surrounding said tube and engaging said propeller element, said screw member having its inner 15 end connected with said barrel to hold it against longitudinal displacement but free 20 for rotation with respect to said barrel and to said lead-tube, and having connected for rotation with said rotatable element a turning member which is exteriorly accessible to the fingers and arranged beyond the forward 25 end of the barrel, and a tip structure extending from said turning member to a point beyond the end of the lead-tube, and being free from the latter and demountably attached to the barrel-carried structure.
- 30 2. In a pencil mechanism of the character described, the combination with a barrel, of a central lead tube adapted and arranged to receive the entire rear portion of a lead structure and rigidly connected with said barrel, a propeller element having a portion entering said tube and a portion outside of said tube adapted to engage a screw member to be propelled thereby, a rotatable screw member surrounding said tube and at 35 its rear end entering within said barrel and there secured against longitudinal displacement relative to said tube or the barrel, and a tip-structure surrounding the forward portion of said screw member and lead-tube and at its rear end detachably connected with the rotatable screw member.
- 40 3. A structure set forth in claim 2 wherein said rotatable screw member has a turning member beyond the end of the barrel and exteriorly accessible and said tip-member has a rearwardly extending part entering within said turning member for detachable connection with said rotatable screw member.
- 45 5. In a pencil mechanism of the character described, the combination with a barrel, of a central lead tube rigidly connected with said barrel to be held by it against rotation, a propeller element having a portion entering said tube to act against the lead and having a portion outside of said tube adapted to engage a screw member to be propelled thereby, a screw member surrounding said tube and engaging said propeller element, said screw member having its inner end connected with said barrel to hold it against longitudinal displacement but free for rotation with respect to said barrel and to said lead-tube, and having connected for rotation with said rotatable element a turning member which is exteriorly accessible to the fingers and arranged beyond the forward end of the barrel, and a tip structure extending from said turning member to a point beyond the end of the lead-tube, and being free from the latter and demountably attached to the barrel-carried structure.
- 50 6. In a pencil mechanism of the character described, the combination with a barrel, of a central lead tube rigidly connected with said barrel to be held by it against rotation, a propeller element having a portion entering said tube to act against the lead and having a portion outside of said tube adapted to engage a screw member to be propelled thereby, a screw member surrounding said tube and engaging said propeller element, said screw member having its inner end connected with said barrel to hold it against longitudinal displacement but free for rotation with respect to said barrel and to said lead-tube, and having connected for rotation with said rotatable element a turning member which is exteriorly accessible to the fingers and arranged beyond the forward end of the barrel, and a tip structure extending from said turning member to a point beyond the end of the lead-tube, and being free from the latter and demountably attached to the barrel-carried structure.
- 55 7. In a pencil mechanism of the character described, the combination with a barrel, of a central lead tube rigidly connected with said barrel to be held by it against rotation, a propeller element having a portion entering said tube to act against the lead and having a portion outside of said tube adapted to engage a screw member to be propelled thereby, a screw member surrounding said tube and engaging said propeller element, said screw member having its inner end connected with said barrel to hold it against longitudinal displacement but free for rotation with respect to said barrel and to said lead-tube, and having connected for rotation with said rotatable element a turning member which is exteriorly accessible to the fingers and arranged beyond the forward end of the barrel, and a tip structure extending from said turning member to a point beyond the end of the lead-tube, and being free from the latter and demountably attached to the barrel-carried structure.
- 60 8. In a pencil mechanism of the character described, the combination with a barrel, of a central lead tube rigidly connected with said barrel to be held by it against rotation, a propeller element having a portion entering said tube to act against the lead and having a portion outside of said tube adapted to engage a screw member to be propelled thereby, a screw member surrounding said tube and engaging said propeller element, said screw member having its inner end connected with said barrel to hold it against longitudinal displacement but free for rotation with respect to said barrel and to said lead-tube, and having connected for rotation with said rotatable element a turning member which is exteriorly accessible to the fingers and arranged beyond the forward end of the barrel, and a tip structure extending from said turning member to a point beyond the end of the lead-tube, and being free from the latter and demountably attached to the barrel-carried structure.
- 65 9. In a pencil mechanism of the character described, the combination with a barrel, of a central lead tube rigidly connected with said barrel to be held by it against rotation, a propeller element having a portion entering said tube to act against the lead and having a portion outside of said tube adapted to engage a screw member to be propelled thereby, a screw member surrounding said tube and engaging said propeller element, said screw member having its inner end connected with said barrel to hold it against longitudinal displacement but free for rotation with respect to said barrel and to said lead-tube, and having connected for rotation with said rotatable element a turning member which is exteriorly accessible to the fingers and arranged beyond the forward end of the barrel, and a tip structure extending from said turning member to a point beyond the end of the lead-tube, and being free from the latter and demountably attached to the barrel-carried structure.

rounding said lead-tube and engaging said screw sleeve and a portion entering the lead tube to engage a lead stick therein.

5. In a pencil of the character described, the combination with a barrel open at its end, of a central slotted lead tube to receive and frictionally hold the lead, said tube shallowly entering and secured in the open end of said barrel, a rotatable screw sleeve surrounding said lead tube and secured against axial displacement from said barrel, a propeller element engaging the thread of the screw sleeve and entering the lead guiding tube, and a tip structure, having a lead guiding orifice at its forward end, detachably mounted on said screw sleeve structure.

6. In a pencil of the character described, the combination of a barrel, a feed structure permanently connected with said barrel, comprising a fixed lead tube adapted to receive and frictionally hold the lead and having a slot, a propeller member entering said slotted tube, a feed screw member surrounding and rotatable about the tube and engaging said propeller member to feed it, and a tip structure detachably engaging the feed screw structure, whereby the tip may be removed without displacement of any lead-feeding part.

7. A structure as set forth in claim 6, wherein said feed-screw structure has an externally accessible turning member of greater diameter than the tube and said tip structure engages said turning member, combined with a tip-carried guide arranged near its rear end to receive and guide the screw member.

8. In a pencil of the character described, the combination of a barrel, feed-mechanism carried by the barrel and presenting a slender stem-portion of the feed mechanism protruding beyond the end of the barrel, a tip-structure detachably connectible with the barrel-carried mechanism to encompass said slender stem-portion and extend taperingly therebeyond, the forward end of the tip being constructed for engagement with a lead stick to carry the lead stick with it on removal of the tip from the feed mechanism, and a guide-member, of smaller bore than the rear end of the tip-structure and carried by said tip in position back of that occupied by the rear end of a tip-carried lead-stick, said stem portion of the feed mechanism and bore of said guide having relatively long, cylindrical cooperating guide surfaces adapted and arranged positively to align the feed-mechanism stem with a tip-carried lead-stick before the forward end of said stem encounters the rear end of said lead-stick.

9. In a pencil of the character described, the combination of a barrel, feed mechanism carried by the barrel and presenting a rela-

5 tively slender stem portion of said feed mechanism protruding beyond the end of the barrel, said feed mechanism having capacity to receive a lead stick of predetermined length and including a lead-tube open at the front end of said stem portion; a 10 tapered tip-member of substantially barrel-diameter at its rear end and small diameter at its front end, said front end of said tip being constructed for engagement with a lead-stick to carry the lead-stick therewith on removal of the tip from the feed mechanism, said tip being detachably connected with the barrel-carried mechanism; and an 15 elongated guide member secured to said tip, said guide member and stem-portion having cooperating cylindrical guide-surfaces of substantial longitudinal extent to insure accurate guidance of the stem axially of the tip, and said guide-member of the tip being arranged well in rear of the position occupied by the rear end of the tip-carried lead-stick to insure accurate alignment of the lead-tube with the lead-stick before said 20 lead-tube can encounter the rear end of said lead-stick.

10. In a pencil mechanism of the character described, the combination with a barrel open at its end, of a thimble shallowly seated in said barrel and fixed therein, a fixed slotted lead-tube carried by said thimble and extending beyond the open end of the barrel and spaced apart from said thimble sub-

stantially to the rear end of the latter; a 35 rotatable screw sleeve surrounding said lead-tube and at its rear end, adjacent the rear end of the thimble, held against longitudinal movement in or removal from the barrel and at its forward end projecting well beyond the barrel and presenting a slender 40 cylindrical guide surface surrounding and concentric with said lead-tube; a propeller member engaging said screw sleeve and having a portion entering the lead-tube to engage a lead-stick therein and thereby determine the length of lead-stick which said feed mechanism may handle; a tip-structure tapering from substantially barrel size at its rear end to a relatively small diameter at its forward end and at its forward end 45 constructed for engagement with the lead-stick to carry the latter with the tip on removal of the tip from the feed mechanism; and a guide member carried by the tip adjacent the rear end of the latter and having 50 a relatively-slender guide cylinder arranged well in rear of the position occupied by the rear end of the tip-carried lead-stick, to cooperate with the guiding surface of said 55 screw member and direct the lead-tube into 60 positive alignment with the tip-carried lead-stick, said slender cylindrical portion of the guide entering the space between the screw sleeve and the thimble when the parts are assembled substantially as described.

GEORGE HOFMANN.
